UNITED STATES PATENT OFFICE.

DAVID W. ANDERSON, OF STOCKWELL, INDIANA.

UNIVERSAL GOLF CLUB.

Application filed May 28, 1927. Serial No. 195,049.

The object of this invention is to enable one golf club to do the work of a whole bag of clubs. To that end, this club is formed of adjustable parts adapting the one club to perform the functions of a plurality of clubs as heretofore made and used. Therefore, the one club will serve as the driver, the cleek, the midiron, the mashie, and the niblick. In other words, the one club will do the work of a bag of different clubs, as its parts are adapted to change the form of the club to be similar to the form of any or all of the clubs heretofore in use.

One feature of the invention consists in connecting the handle and head of the club with a ball and socket joint connection which permits adjustment of the loft of the head and of the lie thereof.

Another feature of the invention consists in means for adjusting the length of the club.

Another feature of the invention consists in providing the head with a series of substantially horizontal ribs with intervening slots or by perforations, through the head for the free passage of air for the purpose indicated, and this also will prevent the atmospheric disturbances of the lie of the ball which is common with clubs as heretofore used.

The full nature of the invention will be understood from the accompanying drawing and the following description and claims:

In the drawings, Figure 1 shows a golf club with the head in elevation and the handle and its connection with the head in central longitudinal section, the club being broken away between its ends as indicated, and showing the club substantially adjusted in its form to serve as a driver. Fig. 2 is a substantially similar figure of the same club adjusted to a different form substantially as desired to serve as a midiron. Fig. 3 is a substantially similar figure, showing the adjustment of the same club to serve as a niblick. Fig. 4 is a plan view of the head and the shank thereof as shown in Fig. 1, the other parts of the club being removed. Fig. 5 is a perspective view of the shank of the head and the lower part of the handle slightly separated to show the relative inclinations of the two adjacent ends thereof. Fig. 6 is a cross section on the line 6—6 of Fig. 1, showing the parts of the handle in position for being moved for the longitudinal adjustment of the handle. Fig. 7 is the same as Fig. 6 with the parts in position when the handle is locked into position after adjustment. Fig. 8 is a central vertical section of the outer sleeve of the upper part of the handle and an elevation of a portion of the inner tube of the handle, the same being broken away at the top and bottom thereof.

A golf club consists essentially of the handle, the head, and the connection between the head and the handle. In this invention these three parts are capable of adjustment to produce all varieties of forms of the usual plurality of golf clubs. This is accomplished by adjusting the loft of the head with relation to the handle, adjusting the lie-angle of the head, with relation to the handle, and adjusting the length of the handle. The character of the construction and the nature of these adjustments will more fully appear in the following explanation.

In the drawings there is shown a golf club head 10 of usual form with a peculiar shank 11 integral therewith and adapted to be secured to the lower member 12 of the handle. The shank 11 is hollow and the lower portion internally threaded to receive a plug or dust cap 13. The upper portion 111 of the shank 11 is hemi-spherical with a central opening 14 in the upper end thereof. The lower tubular member 12 of the handle has a spherically-disposed socket at its lower end adapted to fit on said spherical top of the shank 11, as shown in Fig. 1, and it is held thereon by a connecting rod 15 having a hemi-spherical ball 16 on the lower end, fitting in the upper portion of the shank of the head of the club; thus providing a ball and socket connection between the shank 11 and the lower tubular member 12 and the upper portion of said rod 15 is provided with left-hand threads 17 which screw into the main metal tubular member 18 of the handle. This tube 18 extends for almost the entire length of the handle and its lower end is conical and tapers so as to have a wedge fit in the flaring upper end of the handle member 12, as seen in Fig. 1.

It is apparent that when the rod 15 is tightened by turning the handle tube 18, it will be drawn down tightly into the lower handle member 12 and the ball 16 on the lower end of the connecting rod 15 will be drawn up tightly in the upper part of the shaft 11 of the head so as to make a very firm, strong union between the head and the handle of the club.

The union between the head and the handle of the club is further greatly strengthened by the serrations 20 on the shank of the head 10 and serrations 21 on the lower end of the member 12 of the handle, as shown in Figs. 4 and 5, whereby in any adjusted position of said parts, the serrations of said two members will interengage and lock and prevent any torsional displacement of either the head or the handle relative to each other. The serrations 20 on the shank 11 of the head of the club surround the hemi-spherical portion thereof, as seen in Fig. 1, but an important feature thereof consists in the inclination of the series of serrations 20 with relation to a plane cutting the axis of the handle at a right angle. This inclination is shown to some extent in Fig. 1, and in Fig. 4 the inclination is in the direction indicated by the dotted line 20 of the arrow 22. In other words, those serrations slope downward as indicated by the arrow in Fig. 4.

Such serrations are also shown in Fig. 5. The lower end of the handle has serrations 21 sloping in an opposite direction to the slope of the serrations 20 so that when the lie angle between the handle and the head is modified by turning the handle on the shank of the head, the corresponding modification of the 30 loft of the head will be produced. Therefore, these two adjustments occur simultaneously and relatively. That is, as the lie-angle increases, the loft of the head of the club increases and as the lie-angle of the club decreases, the loft of the head diminishes. This variation is substantially the same as is found in different clubs in a golf bag and is illustrated in the drawings in Figs. 1, 2 and 3. Thus, in Fig. 1, the club has substantially the 35 same form as a driver, or as an iron club when used as a driver. Fig. 2 shows the club in the form substantially of a midiron and Fig. 3 substantially that of a niblick. The drawings are not absolutely accurate reproductions of the forms of the clubs, but are sufficient to illustrate the principle of construction and adjustment of this club and of the form of the variations referred to. Also, the connection between the shank 11 and the 40 tubular member 12 of the handle may be a ball and socket connection without serrations 20 and 21, thus allowing a greater variety of angular adjustments of the lie-angle of the head with respect to the handle and the loft-angle of the head with respect to the handle, which adjustments will neither be arbitrary nor simultaneous with reference to each other but will be entirely at the wish of the operator.

60 In order to enable the relative adjustment of the lower end of the handle and the rounded top of the shank 11 of the head, the slot 14 has a greater diameter than the rod 15, substantially as shown in Fig. 1. The connecting rod 15 has a pin or key 25 in it which

loosely projects into a short longitudinal slot 26 in the lower member 12 of the handle so as to cause the part 12 and the tube 18 of the handle to turn together in tightening them and keep them together during the manipulation of the club while adjusting it. A chamber 27 in the member 12 of the handle surrounds the connecting rod 15 and is sufficient to hold a spiral spring 28 that rests therein and at its upper end engages the 75 lower end of the tube 18 of the handle and at its lower end rests on shoulders 29 in the member 12. The purpose of this spring is to hold the serrations 20 and 21 loosely together during the manipulation of the parts of the 80 club in adjusting the same.

Along with the changing of the loft of the head and the lie-angle of the club, the longitudinal adjustment of the handle is necessary and it cooperates with the other adjustments 85 in order to produce the variety of forms of the club specified. The invention is not limited to any particular construction of the handle for longitudinally adjusting it, but novel and satisfactory means for adjustment 90 are herein shown. The main tube 18 of the handle is surrounded in its upper portion by what may be termed the handle tube 30, as it is grasped by the hand and should be wrapped with leather as is common in golf 95 clubs. This wrapping is not shown for the sake of clearness of the remaining construction. The upper part of the inner main tube 18 has a vertical series of indentations made therein at 31 which is accomplished by stamping inward a series of tongues 32, as seen in Figs. 6 and 7. This leaves a vertical space 100 between the ends of the tongues 32 and the opposite edge of the slot 31. Into this slot projects one or more teeth 33 connected with the outer handle tube 30. These teeth may be formed as shown in Fig. 1, by stamping them in one strip of metal 34 and countersinking it in a corresponding slot in the inner wall of the tube 30. By turning the handle 105 tube 30 on the tube 18 to the positions shown in Fig. 6, the handle tube 30 can be raised or lowered as desired, and when adjusted to the desired position, the handle tube 30 is turned on the tube 18 to the position shown 110 in Fig. 7, where the teeth 33 wedge against the tongues 32 and lock said two handle members firmly together. In this way the length of the handle can be adjusted to suit 115 the lie-angle and the loft of the head.

The head of the club 10 is provided with a plurality of parallel slotted perforations 40 extending through the head and forming between them a corresponding series of ribs 41. These ribs perform the same function as the 125 ribs in the ordinary ribbed head of a golf club, but the slotted perforations are for the purpose of reducing the resistance of the air to the movement of the head of the club and also to reduce the movement of the air by the 130

head of the golf club in driving. From this follow two important results: The reduction of the resistance of the air to the swing of the club gives the club greater driving force.

5 The reduction of the air movement by the club avoids disturbing the lie of the ball. The head of the club is also provided with a number of round holes or perforations 42, as shown in Fig. 1.

10 The invention is not limited to any particular form of these perforations through the head of the club for any perforations would to some extent perform the functions specified, but it is considered desirable to 15 provide the ribs 41 and the longitudinal slotted perforations 40 between them, as shown, as the ribs are desirable to prevent the slippage of the ball on the club.

15 The threads 17 of the connecting rod 15 and the connection between the handle member 30 and the tube 18 are such that the strain on the head 10 resulting from the stroke of the ball or striking the earth during the stroke, tends to tighten both of said 20 connections. Thus the threads 17 are left-hand threads in a right-hand club, and the tongues 32 in the tube 18, as seen in Fig. 7, are on the right-hand side of the pins or 25 projections 33 secured to the handle sleeve 30. In a left-hand club, the reverse construction would be employed.

30 From the foregoing, it is seen that a player can with this single club do substantially the complete play or work that is performed 35 with a bag full of clubs and the alterations or adjustments can be very quickly effected and without any tools. Thus if the player were to drive with the club in the position shown in Fig. 1 and wanted to use a mid-iron, he would adjust the club by changing 40 it to the form shown in Fig. 2 by giving the handle a slight turn so as to loosen it and change the adjustment with relation to the shank of the head of the club, and then a 45 reverse turn of the handle tighten it, and a slight movement of the handle tube 30 and then a slight longitudinal movement thereof and then a return turning movement of the same, will adjust the length of the handle. Thus the handle can be modified from 50 the length of a driver handle to the length of a putter handle almost instantly. These 55 adjustments would ordinarily be done while walking and approaching each ball and need not delay the game. This not only gets rid of a bag of clubs, but gets rid of a caddie.

The invention claimed is:

1. A golf club including a head having a shank, a handle, and a ball and socket connection between the head shank and the handle permitting their angular adjustment, the adjacent surfaces of said two members being serrated for engaging each other and said serrated surfaces being inclined to the axis 60 of the handle, whereby when the head or

the handle may be turned relative to each other, the lie-angle and the loft of the head will be simultaneously and correspondingly varied.

2. A golf club substantially as described 70 in claim 1, said serrated surfaces being inclined upward towards a position at the rear of the top line of the head, whereby the lie-angle and loft will be correspondingly reduced or increased in the adjustments 75 of the connection between said handle and the head.

3. A golf club including a head having an integral shank with an upper hemi-spherical shell having an upper central opening and 80 a series of radial serrations surrounding the lower part of said shell, a handle provided at its lower end with a socket to receive said shell, a series of serrations at the lower end of the handle engaging the serrations 85 surrounding the shell, a connecting rod extending through the opening of said shell and having a ball on its lower end fitting in the shell, and means for adjustably securing said rod in the handle, whereby the head and handle can be adjustably secured together. 90

4. A golf club including a head having an integral shank with an upward hemi-spherical shell having an upper central opening and a series of radial serrations surrounding the lower part of said shell, a handle having a lower member provided with a socket at its lower end to receive said shell on the shank of the head, a series of serrations at 100 the lower end of the handle for engaging the serrations on the head of the shank, a handle tube with its lower end in wedging engagement with the lower member of the handle, a connecting rod extending through said shell on the shank of the head and said handle member, and a ball on the lower end of said rod fitting in said shell and with the upper end in threaded engagement with the handle tube, whereby the head and handle can be adjustably secured together. 105

5. A golf club substantially as described 110 in claim 3, with the opening in the top of said shell head being larger than the connecting rod between said shell and handle.

6. A golf club substantially as described 115 in claim 3, with a spring between said two members of the handle for lightly holding the serrated surfaces in engagement during said adjustment.

7. A golf club substantially as described 120 in claim 3, with the upper end of the lower member of the handle flaring and the lower end of said handle tube tapering to fit and wedge therein when the parts are adjusted.

8. A golf club having a handle including 125 a main handle tube, a handle sleeve loosely surrounding the upper portion of said tube, the upper part of said handle tube having a vertical row of tongues stamped inward, and a key secured to and extending from said 130

handle sleeve and adapted to enter any one of the grooves formed by stamping in said tongues, whereby the length of the handle may be vertically adjusted and held in adjusted position by turning one of said handle members with reference to the other.

9. A golf club having a handle substantially as set forth in claim 8, the upper part of said handle tube having a vertical row of 10 tongues stamped inward, and a key secured to and extending from said handle sleeve and adapted to enter any one of the grooves formed by stamping in said tongues, whereby the length of the handle may be vertically 15 adjusted and held in adjustable position by turning one of said handle members with reference to the other, the relation of the

tongues and key being such that the connection between the two handle members will tighten as a result of the tendency of the head 20 to turn during a stroke.

10. A golf club including a head having a shank, a handle, a ball and socket connection between the head shank and the handle permitting their angular adjustment, the adjacent surfaces of said two members being serrated for engaging each other, and the ball and socket connection adapted to draw the handle and head shank tightly together 25 whereby they will be located in adjusted 30 position.

In witness whereof, I have hereunto affixed my signature.

DAVID W. ANDERSON.
